CONTAINER CLOSURE

Oscar W. Wentz, Long Island City, N. Y.

Application March 1, 1937, Serial No. 126,351

9 Claims. (Cl. 229—17)

This invention relates to container closures, particularly for containers made of materials like paper, cardboard, and the like.

One of the objects of this invention is to provide simple and inexpensive means for maintaining closed the end of a container that is made up of material like paper, cardboard, or the like, and capable of having its end portions folded into container-closing position or relationship, and to provide means of this character that will be easy to apply to the closed or folded container end and capable also of ease of subsequent manipulation for opening and closing the container. Another object is to provide a closure-maintaining means or device of the above-mentioned character that will be capable of having various indicia related thereto in a simple and inexpensive manner, as by printing, particularly with respect to containers intended for use in milk distribution where it is frequently required that the container indicate the date of filling and where it is also desirable to indicate the character or grade of the liquid contents. Another object is to provide a closure-retaining means or device which can be readily and inexpensively incorporated into the usual routine of filling, closing and closure-clamping operations upon the container. Another object is to provide a device of the above-mentioned character which can be easily and inexpensively incorporated into such routine and to relate to the latter an appropriate step of applying to the closure-maintaining device the desired indicia. Another object is to provide an efficient and dependable method of filling, dating or otherwise applying desired indicia and closing containers such as in the milk-distribution industry.

Another object is to provide a closure-maintaining device which can be easily manipulated to release the folded or closed container end, as for the purpose of withdrawing some of the contents of the container, and then to restore the closure-retaining device after the container end has been restored or folded to closed position. Another object is to provide a simple, practical and efficient closure-maintaining device of the above-mentioned character that will be well adapted to meet certain peculiar and varying conditions of practical use. Other objects will be in part obvious or in part pointed out herein-after.

The invention accordingly consists in the features of construction, combinations of elements, arrangements of parts and in the several steps and relation and order of each of the same to one

or more of the others, all as will be illustratively described herein, and the scope of the application of which will be indicated in the following claims.

In the accompanying drawings in which are shown several of the various possible embodiments of the mechanical features of my invention,

Figure 1 is a diagrammatic representation of an illustrative apparatus for carrying on certain steps in the making of the closure-retaining device of my invention;

Figure 2 is a transverse sectional view on an enlarged scale, as seen along the line 2—2 of Figure 1, showing the closure-retaining means in one stage of its construction;

Figure 3 is a diagrammatic representation of a mechanism illustrating certain subsequent steps that are performed;

Figure 4 is a detached perspective view of the relationship between the closure-retaining device and a container whose end has been folded into closing position or relationship in the illustrated manner shown in Figure 4;

Figure 5 is a view showing the container with the closure-retaining device in place;

Figure 6 is a perspective view showing the manner in which the closure-retaining device or a portion thereof may be manipulated subsequently and also certain folds of the container manipulated to bring about withdrawal of the contents of the container;

Figure 7 is a perspective view of a container showing another possible form of folding to effect a closure thereof and another manner in which the closure-retaining device may be related thereto;

Figure 8 is a vertical sectional view on an enlarged scale, as seen along the line 8—8 of Figure 7, and

Figure 9 is a development of a closure-retaining device showing certain preferred modifications.

Similar reference characters refer to similar parts throughout the several views in the drawings.

As conducive to a clearer understanding of certain features of construction and action of my closure-retaining device reference might first be made to Figure 4 in which is shown a container made, for example, of a suitably heavy paper or appropriate weight of cardboard and having an upper portion provided with appropriate crease or fold lines whereby the upper portion may be folded preferably to provide a substantially straight-line upper edge along which the

upper edges of the container material are alined and interfolded. Thus, by way of illustration of one type of foldable container closure to which my retaining device is applicable, the illustrative container 10 of Figure 4 has two opposed panels 11, 12 which are at their upper edges or ends brought substantially into contact with each other, and appropriately shaped panels at the right-hand end to provide a double fold 13 that extends in between the right-hand portions of 10 the upper edges of the panels 11-12; at its left-hand end the container construction has crease or fold lines so that two double folds 14 and 15 may be effected and swung against the outer faces of the panels 11, 12, respectively. In this illustrative manner the upper edge portions of the container become subdivided, folded over and against each other, illustratively all along a straight line, and thus the upper end of the container is closed.

In Figure 4 is shown, in perspective, a preferred form of closure-retaining device according to my invention and it is generally indicated by the reference character 16. At an appropriate stage, as is later pointed out, the device 16 is given a cross-section that is that of an inverted U, as shown in Figure 4, so that it may be seated over the alined folded upper edge of the container 10 and brought into a clamping relationship to the various folds to hold them 30 in closing position.

In considering the structural features of the device 16 it may be helpful to consider one possible way of constructing it and hence reference may now be made to Figure 1. In Figure 1 I have shown at 17 and 18 two opposed pressure rolls having preferably yielding surfaces as, for example, may be arranged by providing the peripheries of the rolls 17, 18 with a suitable layer of rubber appropriately yieldable so that the rolls may conform to certain variations or differences in thicknesses of the material that is passed therebetween. Any suitable means, not shown, may be provided to press the rolls toward each other with a suitable pressure and also to drive one or both of them in directions to effect a feeding movement toward the right of the material operated upon by the rolls.

In between the rolls are fed two webs 19 and 20 of paper and preferably web 19 is somewhat wider than web 20. Web 20 could be of a width, for example, just about equal to the over-all length of the top folded or edge portion of the container 10 of Figure 4.

As the webs 19 and 20 are fed to the opposed pressure rolls 17-18 their adjacent faces have applied to them, by any suitable means diagrammatically indicated at 21 and 22, respectively, a suitable adhesive, such as glue, cements in paste-like form, and the like, and also fed in between the two pressure rolls but in between the opposed faces of the webs 19 and 20 which have the adhesive thus applied to them, is a plurality of strips of sheet metal; illustratively, I have indicated in Figure 1 three such sheet metal strips at 23, 24 and 25.

The middle strip 24 is preferably alined with the center line of the narrower web 20 while the outside edges of the outside strips 23 and 25 are preferably alined with the outer longitudinal edges of the narrower web 20.

As the webs and sheet metal strips are thus operated upon by the pressure and feed rolls 17, 18, the adhesive acts to secure the two webs to 75 the respective faces of the metal strips and also

to secure together the webs themselves in the regions intermediate of the metal strips themselves. Thus, there results a laminated structure as it emerges to the right of the pressure rolls 17, 18, the yieldable surfaces of the pressure rolls insuring that the parts are dependably pressed together both where sheet metal is interposed between the webs and where no sheet metal is thus interposed.

Thereafter, a suitable guiding or folding means, diagrammatically indicated in Figure 1 at 27 and 28, folds the two marginal portions 19^a and 19^b of the lower or wider web 19 over onto the upper face of the longitudinal marginal portions of the web 20 and to an extent depending upon the width of these marginal portions 19^a, 19^b. Illustratively, they may be of a width approximating the width of the outside sheet metal strips 23 and 25, and since the marginal portions 19^a, 19^b bear adhesive on their upper faces, they become turned down upon the upper marginal portions of the web 20 and glued thereto. Suitable pressure rolls 29 and 30 may be employed, if desired, to press these overturned marginal portions 19^a, 19^b down into their folded position and insure that the adhesive thereon retains them in place.

In Figure 2 is shown in section the resultant band-like laminated construction, it being noted that preferably all of the contacting surfaces or faces, as shown in Figure 2, are adhesive-bearing and have been tightly pressed together and are thus dependably secured together. Furthermore, the adhesive acts much like a sizing to the paper, particularly in the regions intervening the sheet metal strips 23, 24, 25.

From the band-like laminated material thus formed suitable lengths may be cut off and bent into the U-shaped form shown at 16 in Figure 4 for application to the closed end of the container.

However, since containers, as, for instances, in the milk-distribution field, are filled, closed and sealed mechanically, I may in such cases relate, if desired, such apparatus as I describe above in connection with Figure 1, directly to the apparatus and mechanism for handling the containers. For example, and referring to Figure 3, I have there diagrammatically shown at 31 a conveyor along which containers 10, appropriately spaced, are moved, preferably intermittently, and thus successively brought into operative relationship to appropriate mechanisms or stations. Thus at A is diagrammatically indicated a filling station or mechanism of any suitable type for measuring out a suitable quantity of material, such as milk, and pouring it into the container at that station.

At B is diagrammatically indicated the next station to which the now filled container is brought and at this station the upper portions of the container are folded, for instance, in the manner shown in Figure 4 and described above. At that station or at a subsequent station, the band-like laminated material as it emerges from, for example, the pressure rolls 29 and 30 of Figure 1, is cut off in appropriate lengths, bent into the above-mentioned inverted U-shape, as shown in Figure 4, brought down upon the upper folded closed end of the container 10, and then lateral pressure applied by any suitable means to bring the two sides of the inverted U-shaped cross-section toward each other and thus securely clamp the folded container top against unfolding, opening, or separation. The mecha-

nism or means for thus cutting off this material, bending it and applying it in clamping relationship to the container top may take any suitable or appropriate form and in Figure 3 is diagrammatically indicated by the reference character 32. The mechanism 32 is, of course, appropriately timed or synchronized with respect to the operations at the preceding stations, such as stations A and B.

Particularly in the field of distribution of milk, it is desirable to indicate the grade or quality of the contents of the container, also quantity in the container, and also the date of filling. Accordingly, I may and preferably do provide suitable means, preferably operating just in advance of the mechanism 32 of Figure 3, for applying such indicia at appropriate intervals upon the band-like laminated material as it emerges from the pressure rolls 29, 30. By way of illustration, such indicia may be applied as by printing directly upon the outer face of that web, illustratively web 19, which, in the U-shaped device 16 of Figures 4 and 5, is to be the outer web.

This printing may be effected by means diagrammatically shown in Figure 1. Thus, for example, I may provide a suitable support or platen, illustratively in the form of a roller 33, over which the laminated material moves in a direction toward the right, and thus to support the material appropriately to permit a suitable printing device 34, illustratively in the form of a printing roller, to impress upon the lower face of the laminated band the data or indicia that it is desired to print thereon.

Preferably the printing device 34 applies indicia in two lines within the area or section of the laminated band material that is to become a single closure-retaining device like that of Figures 4 and 5. For example, let it be assumed that the right-hand end of the material is to be cut off, in the mechanism 32 (Figure 3) along the two lines C, D, that being the section needed to be bent into the inverted U-shape, as above described. Accordingly, one line of printing can be positioned relatively close to the line C and the other line of printing relatively close to the line D, the one line being inverted with respect to the other so that when the cut-off section is bent into U-shaped form by the mechanism 32 of Figure 3 and applied to the container, both sides of the container appear with the identifying data, or the like, and both printed matters read right side up.

In Figure 4 illustrative printed matter is indicated and preferably it is applied to the thicker or elevated parts of the material, being those parts that overlie the sheet metal strips 23, 24, 25.

In applying the device 16 to closure-retaining relationship, illustratively by the mechanism 32 of Figure 3, it is preferable that the clamping-pressure-applying means operates independently in as many regions as there are sheet metal strips within the device; thus, where three sheet metal strips are employed, as in the illustrative embodiment, three pairs of clamping-pressure-applying means are preferably employed so that each sheet metal portion of the device 16 may be dependably accommodated to the particular thickness of folded-over container edge which it is to clamp. For example, and referring to Figure 4, the sheet metal part of the member 16 at its right-hand end is made operative upon four thicknesses of paper, due to the inturned double fold 13; at the central portion of the container

closure, however, there are in the illustrative closure, only two thicknesses of material or paper and the middle or central sheet metal strip in the device 16 can be made dependably effective upon these two thicknesses. Where the left-hand end of the container is folded over, as shown in Figure 4, it will be seen that there are six thicknesses of paper, but throughout this region the left-hand sheet metal strip in the device 16 can be dependably accommodated to that greater number of thicknesses. Also, if desired, the thicknesses of the sheet metal strips employed may be varied rather than made uniform throughout. For example, it may be preferable to make the left-hand sheet metal strip in Figure 4 thicker than the rest in order to insure, if found desirable, a stronger clamping pressure at that end of the container.

In use, the closure-retaining device is strong and dependable, its indicia is clearly legible, the construction permitting the use of relatively large printing type. Also, the device 16 will be seen to be substantially entirely encased in paper, substantially free from protruding sharp metal edges, and thus the closure is substantially free from affording injury to the fingers or the hand.

When it is desired to obtain access to the contents of the container, it is possible to do so by unbending only one end of the entire device 16, illustratively the left-hand end, as viewed in Figures 4 and 5, particularly where it is at that end that the container top portion is folded to permit of easy unfolding, as, for example, to form a pouring spout out of the unfolded double folds 14 and 15.

In such case, the left-hand portion of the device 16 preferably has printed upon it a suitable indication that that is the end of the entire device 16 that should be undone, and, illustratively, such an indication might comprise the words "Lift up," as indicated in Figures 4 and 5.

Accordingly, one arm of the U-shaped left-hand end portion of the device 16 is lifted up or unbent, assuming a position or relationship like that shown in Figure 6, whence the double folds 14, 15 may be unfolded into the spout 36. In this process of unbending only one of the U-shaped sheet metal members, a portion of the intervening paper may or may not tear; in Figure 6 I have indicated at 37 a partial fracture or tearing of the paper intervening the two left-hand sheet metal strips, the remaining or un torn portion of the paper maintaining the upwardly bent left-hand portion assembled to the entire construction and in fact appropriately positioned for restoration when the spout 36 is folded back into the relationship shown in Figures 4 and 5. This clamping operation to restore the closure is one, moreover, that may be manually achieved for it is not necessary, in restoring the device to closure-retaining position to contend with any mechanical resistance on the part of other or the remaining sheet metal portions of the device 16.

Thus, it will be seen that the construction is thoroughly practical and has numerous important advances; for example, I have indicated how it may be incorporated into the routine steps of filling, closing and sealing containers, as, for example, in the milk distribution field. However, it will be apparent in view of the foregoing, that my device 16 may be applied to closure-retaining relationship by hand instead of by ma-

chinery and in that connection the manual operation, it is to be noted, may be easily carried on since, considering now Figures 4 and 5, the clamping pressure may be applied successively to the various sections that encase the sheet metal strip or clamping member.

In Figure 7 I have shown, by way of illustration, another possible form in which my device may be related to a container closure. The device is indicated by the reference character 38 and is substantially similar to the device 16 of Figure 4 excepting that it is not yet bent into the inverted U-shape. Here the container 40 is again illustratively made of paper, has two opposed panels 41 and 42 which are bent toward each other to bring their upper edges in alignment, the opposed ends of the upper portion of the container being suitably folded, illustratively inwardly at both ends, as at 43 and 44, when it is desired to effect closing of the container.

To one of the opposed panels, illustratively panel 42 (see Figure 8) is applied the unbent device 38 in any suitable manner, but preferably as by an adhesive, as indicated at 45, the unique features of my invention permitting the use of a suitable adhesive in that the adhesive operates upon and secures together two paper parts, it being borne in mind, and as shown in Figure 2, that the sheet metal parts are completely encased in paper.

Accordingly, containers may be made up in the manner shown in Figures 7 and 8 with the closure-retaining device 18 applied thereto and the containers distributed in the usual manner for use, as, for instance, for over-the-counter sale or distribution of products. The container having been filled to the desired extent with the desired product, its upper end is brought into straight-line closing relationship by folding, as shown in Figure 7 and as already above-described, whence the device 38 is bent into closure-retaining or clamping relationship, the U-shaped form like that shown in Figure 5, by operating successively upon the different sections of the device 38 corresponding to the number of sheet metal strips which it embodies. Generally one single bend, hence a bend into U-shaped form, as just noted, will suffice but, if desired, the vertical dimension of the device 8, as shown in Figure 8, may be increased or made longer in a downward direction, and the upper closed end of the container virtually rolled up throughout one or more turns, along with the vertically elongated device 38.

For opening the container of Figure 7, the manipulation of the device 38 will be clear in view of what has been set forth above in connection particularly with Figure 6. Or if a rolling-up operation has been resorted to, it suffices simply to unroll the rolled-up parts.

Preferably, the line along which the cut-off mechanism 32 operates is not a straight line, as is indicated in Figure 1, and if the cut-off line has a shape like that shown at C and D in Figure 1, the effect upon the final retaining device 16 is to give the left-hand clamping element thereof a tab 46 which projects downwardly, as viewed in Figures 4, 5 and 6, from the legend "Lift up," forming a convenient tab, which is preferably left in a slightly outwardly projecting relationship, as shown in Figure 5, to permit easy access thereto by a finger of the hand or even the fingernail to unbend the left-hand portion of the device 16 when it is desired to gain

access to the contents of the container. Similarly, the device 38 of Figure 7 may be provided with one or more such tabs 47.

In Figure 9 I have shown a development of the device 16 or 38 illustrating how, by varying the shape of the cut-off line additional advantages may, if desired, be obtained. Illustratively, the line of cutting where the sheet metal strip 23 extends may be shaped to provide the tab 48, 10 like the tabs 46 or 47, above described, but in such a way that there is left in the two opposed edges of the sheet metal part 23 relatively sharply defined portions E which, under the action of the pressure which is applied to effect the 15 clamping can be made to bend and bite into the material of the container. In a like manner the line of cutting at the other metal parts, such as the parts 24 and 25, may be given a configuration, as is generally indicated in Figure 9, to provide parts F along one edge and staggered parts 20 G along the opposed edge which likewise can be made to be bent or bite into the material of the container. Thus, a more secure gripping is achieved and a tighter fastening of the retaining 25 device to the closure of the container achieved. Also, by staggering opposed parts, as above suggested and by applying appropriate clamping pressures, the lower edges of the sheet metal 30 portions of the device when in U-shaped form can be made, with the straight-line folded closure-forming parts of the container, to partake of a wavy or corrugated effect, an effect which can be made to achieve great security and tightness of fastening and sealing.

35 It will thus be seen that there has been provided in this invention a container closure-retaining device in which the several objects hereinbefore set forth, together with many thoroughly practical advantages are successfully achieved. 40 It will be seen that the device is simple, inexpensive and rugged in construction, capable of ease of manipulation and is, moreover, well adapted to meet the widely varying conditions of practical use.

45 As many possible embodiments may be made of the mechanical features of the above invention and as the art herein described might be varied in various parts, all without departing 50 from the scope of the invention, it is to be understood that all matter hereinabove set forth, or shown in the accompanying drawings, is to be interpreted as illustrative and not in a limiting sense.

I claim:

55 1. The combination with a container made of paper, or the like, having an otherwise open end closable by folding the end portions of the container wall together, one portion of said closure being capable of being unfolded to form a pouring spout, and closure-retaining means therefor comprising a unitary clamping structure made up of a plurality of individual U-shaped bendable clamping means, at least one of which is operative upon the spout-forming portions of said closure, and a readily frangible and flexible covering means for covering over all of, and for connecting together and holding, said individual clamping means to form said unitary clamping structure, whereby the latter is as a unit clamped over the folded end of the container and such of the individual clamping means operative upon said spout-forming portion may be operated to release the latter for unfolding to form said pouring spout while leaving the remaining clamping means operative.

2. The combination with a container made of paper, or the like, having an otherwise open end closable by folding end portions of the container wall together to form a straight-line closure having along its length different thicknesses made up of respectively different numbers of layers of the folded end portions, and a unitary closure-retaining means therefor comprising a plurality of individual clamping members of sheet-like material adhesively secured to and encased between two juxtaposed non-metallic sheet materials, the latter being sufficiently yieldable to cause individual clamping members to conform themselves respectively to said differing thicknesses.

3. A construction as claimed in claim 2 in which said individual clamping members are spaced from one another and said two non-metallic sheet materials bridge over the space between the clamping members and are adhesively secured together in said space, the spacing between individual clamping members being sufficient to permit the non-metallic sheet materials that bridge thereover to flex or yield according to the variations in relative positions of the clamping members as affected by said differing thicknesses.

4. The combination with a container made of paper, or the like, having an otherwise open end closable by folding the end portions of the container wall together to form a straight-line closure having along its length different thicknesses made up of respectively different numbers of layers of the folded end portions, and a unitary closure-retaining means therefor comprising a plurality of individual sheet metal bendable members connected together by sheet material like paper adhesively secured thereto, said sheet material being sufficiently yieldable to permit said individual sheet metal bendable members to be bent into clamping positions to conform themselves respectively to said different thicknesses.

5. The method of making a container closure which comprises feeding two webs of non-metallic material like paper and a plurality of flat or plane bendable metal parts interposed therebetween, with adhesive applied to said webs, into and between pressure rolls, whereby portions of said webs become flattened out against and supported by said flat or plane metal parts, printing onto the external surface of the flattened and thus supported portion of at least one of said webs and at intervals spaced therealong appropriate identifying indicia, and severing the band-like material after it emerges from said pressure rolls at intervals commensurate with the intervals of printing to form individual closure-retaining devices each bearing said indicia.

6. The combination with a container made of paper, or the like, having an otherwise open end closable by folding the end portions of the container wall together, one portion of said closure being capable of being unfolded to form a pouring spout, and closure-retaining means therefor comprising a unitary clamping structure made up of a plurality of individual U-shaped bendable clamping means, at least one of which is operative upon the spout-forming portions of said closure, and a readily frangible and flexible covering means for covering over all of, and for connecting together and holding, said individual

clamping means to form said unitary clamping structure, whereby the latter is as a unit clamped over the folded end of the container and such of the individual clamping means operative upon said spout-forming portion may be operated to release the latter for unfolding to form said pouring spout while leaving the remaining clamping means operative, said means holding said individual clamping means together comprising a sheet of tearable fibrous material like paper adhesively related to at least one side of said plurality of individual clamping means, and being capable of being torn along that portion thereof that is adjacent to the adjacent edges of two adjoining individual clamping means.

7. A closure for containers made of a foldable material like paper, or the like, comprising a plurality of substantially aligned bendable metal parts and non-metallic means holding said parts together, the edges of said metal parts having bendable portions capable of being pressed or made to bite into the material of the container.

8. The combination with a container made of paper, or the like, having an otherwise open end closable by folding the end portions of the container wall together, one portion of said closure being capable of being unfolded to form a pouring spout, and closure-retaining means therefor comprising a unitary clamping structure made up of a plurality of individual U-shaped bendable clamping means, at least one of which is operative upon the spout-forming portions of said closure, and a readily frangible and flexible covering means for covering over all of, and for connecting together and holding, said individual clamping means to form said unitary clamping structure, whereby the latter is as a unit clamped over the folded end of the container and such of the individual clamping means operative upon said spout-forming portion may be operated to release the latter for unfolding to form said pouring spout while leaving the remaining clamping means operative, that individual clamping means that is operative upon the spout-forming portions having on at least one arm thereof a tab-like extension forming a finger piece whereby it may be readily unbent.

9. The method of making a container closure which comprises continuously feeding two webs of non-metallic material like paper into face to face relationship with adhesive applied to at least one of the adjacent faces of said webs, continuously feeding in between said two webs a plurality of spaced flat strap-like metal parts, applying pressure to the resultant laminated structure that comprises the two webs with said interposed spaced metal parts so that the adhesive-bearing web is pressed both against the flat faces of said metal parts and against those portions of the other web intervening the spaced metal parts, printing at spaced intervals appropriate identifying indicia onto the external flattened surface of the portion of one web overlying and flattened against and supported by one of said flat strap-like metal parts, and severing the resultant laminated band-like structure transversely thereof at intervals commensurate with the intervals of printing and sufficient to form individual closure-retaining devices each bearing said indicia.

OSCAR W. WENTZ.
